UNITED STATES PATENT OFFICE

RICHARD HOWLAND RANGER, OF NEWARK, NEW JERSEY, ASSIGNOR TO RADIO CORPORATION OF AMERICA, A CORPORATION OF DELAWARE

FACSIMILE SYSTEM

Application filed May 3, 1929. Serial No. 360,064.

The present invention relates to facsimile systems and the like, and is particularly directed to a facsimile system of what I have termed a "combined or universal type".
5 By the term "combined or universal type", I intend to include types of facsimile systems wherein a picture may be built up in a line for line manner, or wherein a picture by making suitable adjustment to the transmitting or receiving apparatus may be built up in a woven manner by crossing and recrossing the lines of scanning and reproducing so as to produce at the receiver end of the system a picture record which more closely approximates the well known and desirable half tone.

While I will herein describe my invention as applicable to transmitting and receiving pictures, it is to be understood in connection with the term "pictures" that I wish to use this term in a generic and not limiting sense, and, therefore, by the term "pictures" I intend to include views, printed matter, checks, finger prints, photographs, 25 financial statements, newspaper articles, advertisements, fashion plates, magazine articles, moving pictures and films, as well as the sound records thereon, and the like.

As one of the primary objects of my invention, I have sought to develop a method and means by which a system for transmitting and receiving pictures may be readily changed from the line for line type of scanning and reproducing into a cross line 30 or woven type of scanning and reproducing machine.

As a still further object of my invention, I have sought to provide a picture transmitting and receiving system wherein the transmitting and receiving apparatus may be readily adapted to either a single channel or multiplex channel transmitting and receiving system so that the entire message which is to be transmitted and received 40 may be transmitted over a single channel of communication or over a plurality of channels of communication. Systems for transmitting a message over a single channel of communication so far as the channelling per se is concerned are known in the art

to which the invention relates, and a system for transmitting and receiving pictures and the like over a plurality of independent channels such as are suitable for multiplex communication systems have been shown 55 and claimed in connection with my copending applications, Serial Nos. 360,066 and 360,068, both of which were filed on May 3, 1929, wherein the first of the said applications relates to an analyzing system for 60 multiplex transmission of pictures and the like, and the second relates to a reproducing system for pictures and the like.

Still a further object of my invention is to provide a method and means by which a picture carrying drum suitable for carrying the picture to be transmitted from the transmitting mechanism or the record upon which the picture is recorded at the receiving mechanism may be advanced with respect 65 to the scanning or reproducing system at different rates and may make either a portion of a complete revolution for each longitudinal movement of the scanning or reproducing system with respect thereto or 70 may make slightly more than a complete revolution for a similar movement of the scanning or reproducing mechanism, depending, of course, upon the type of transmission, as above outlined.

Still other objects of my invention are to provide, in a manner to be hereinafter set forth and described, a system for transmitting and receiving pictures and the like which is relatively simple in its construction 75 and arrangement of parts, a system which is compact, conveniently installed, easily operated, efficient in its use and which may be built at a minimum of expense.

Still other and ancillary objects of my invention will become apparent and at once suggest themselves to those skilled in the art to which the invention relates by making reference to the accompanying drawing wherein the single figure thereof illustrates 80 in a more or less conventional manner the means by which the above outlined objects are attained.

To refer now more particularly to the drawing, I have shown a picture carrying 100

drum 1 which may be either the drum of the transmitting or the receiving machine as being carried at one end by an end supporting member 3 which is fastened and secured to a base member 5 in any appropriate and desired manner. Also, extending parallelly to the picture carrying drum 1, I have provided a rotating shaft 7 upon which an endless spiral 9 has been cut for the purpose of carrying either a scanning or reproducing system in a longitudinal manner back and forth with respect to the drum.

While the scanning and reproducing systems have not been shown, this has been omitted so as to more clearly and definitely illustrate the principles involved by my invention, and for details as to the motion of the scanning or reproducing systems back and forth longitudinally with respect to the shaft 7, reference may be had to my copending application, Serial No. 245,349, filed January 9, 1928, disclosing what I have termed a "photoradioscope" wherein a hot air jet is carried back and forth longitudinally with respect to a recording drum surface and transversely with respect to a paper feed and has been shown as moved in this manner by means of a rotating shaft provided with a similar endless spiral as has been shown by the spiral 9. Similarly, my copending applications, Serial Nos. 235, 431 and 245,350, filed respectively November 25, 1927, and January 9, 1928 disclose respectively scanning and reproducing systems carried back and forth longitudinally with respect to a similar rotating shaft as shown by the shaft 7, and my copending applications, Serial Nos. 321,821, 360,066, and 360,068, filed November 26, 1928, May 3, 1929, and May 3, 1929, disclose respectively an illumination system for illuminating a picture carrying drum, a multiplex analyzing system, and a multiplex reproducing system for use in conjunction with this type of recording apparatus. It should, therefore, be understood that I may provide any type of suitable scanning or reproducing means and support the same upon the shaft 7 so that by rotational movement imparted thereto, so as to rotate the same in the direction shown by the arrow, the analyzing or reproducing system may be moved back and forth thereon in the direction shown by the arrows so as to either illuminate a picture surface carried by the drum 1 or to subject the recording surface carried by the drum 1 to either light in the case of a light sensitive recording system or heat in the case of a heat sensitive recording medium supported by the drum 1. In such a case, the illumination or reproducing system is to be supported and carried upon the supporting plate 11 carried within the guide slots 13 and 15 so as to move in a fixed path of travel

back and forth longitudinally on the shaft 7.

The guide slots 13 and 15 provided for guiding the analyzing or reproducing system carried upon the supporting plate member 11 are preferably mounted in supporting members 17 which are also carried upon and supported from the base member 5 in any suitable and desired manner. If desired, I may provide on the supporting plate 11 suitable rollers for bearing in the slotted guide strips 13 and 15 so as to reduce the amount of friction provided by a longitudinal movement of the supporting plate imparted thereto by the rotation of the rotating shaft 7.

The rotating shaft 7 is turned from any suitable source of rotational movement, and extending out from the end of the shaft which is supported in the supporting member 17, I have provided a pair of gears 19 and 21 respectively, of which 19 is an ordinary beveled pinion and 21 is the usual type of worm gear. Both of these gears cooperate to drive the picture or record carrying drum, in a manner to be hereinafter set forth and described.

For convenience of description, I will describe now the operation or rotation of the picture carrying drum 1 as applied to a line for line scanning or reproducing picture transmitting and receiving process. By the term "line for line," of course, I mean that each line of the picture is adjacent to each other line and extends in a direction substantially longitudinal with respect to a record surface carried upon the drum member 1. As shown, the worm gear 21 is in engagement with a pinion 23 carried upon a shaft 25 provided with collars 27 for the purpose of securely holding the pinion on the end of the shaft. As the shaft 7 turns and imparts rotational movement to the worm gear, the pinion 23 is correspondingly turned and turns therefrom a second pinion 29 of a smaller size than the pinion 23, which is mounted adjacent the last named pinion. As the pinion 29 is rotated, it meshes with still another pinion 31 which is secured to the shaft 33 in any desired and appropriate manner, for example, by a set screw, so that it will now be seen that rotational movement has been imparted to the shaft 33 due to the rotation of the spindle 7.

The shaft 33 extends through a housing 35 provided therein with a gear reducing or changing mechanism, and is appropriately arranged to drive a pinion or gear 37 carried and supported from a shaft 39 so as to rotate the said shaft. The end of the shaft 39 is connected with a differential system conventionally shown as 41 which includes a pinion mounted on the shaft 39 so as to rotate a pair of gears arranged on a spindle extending at right angles to the

shaft and arranged to then drive still another pinion carried upon the end of the shaft 43 which is preferably mounted and supported by bearing surfaces 45 and 47, which may be mounted and secured upon the end support plate 3 in any appropriate and desired manner. Due to the fact that the drive imparted to the shaft 39 from the spindle 7 does not cause any appreciable movement of the differential, the worm gear 49 attached to the shaft 43, and which is in engagement with the large gear 51, serves for the purpose of slowly rotating the gear 51 and thereby turning the drum 1 upon its shaft 53 in any appropriate and desired manner. The rate of turning of the shaft in conjunction with a line for line scanning should be a rate equal and corresponding to the line advance for a single line of the picture, and, for example, supposing that there are eighty lines of scanning to the inch and a single communication channel is used, the amount of rotation of the drum 1 imparted thereto from the turning 25 of the worm and corresponding turning of the gear 51 will be one-eightieth of an inch.

If, however, the system is changed from a single channel communication system to a multiplex channel of communication, and, for example, the number of channels is increased to four, the line advance should be correspondingly increased for each longitudinal movement of the analyzing or reproducing system on the shaft 7. Therefore, I have provided within the housing 35 the usual type of gear shift for increasing the speed of rotation of the shaft 43, and this increased speed may conveniently be provided by merely shifting the gear lever 55 to a different position in the gear shift slot 57 so as to make the position of the gear shift lever or pin 55 correspond in position to the number of channels being used in the communication system.

Thus, it may be seen that I have provided a system wherein the picture may be transmitted or received in a line for line manner by either transmitting and reproducing the picture one line at a time or by a plurality 50 of lines at a time, and, for example, supposing that the gear shift lever or pin 55 is arranged in the position as shown, the system may, for example, be changed into a four channel multiplex communication system, and supposing that the above named example of eighty lines per inch was the amount of detail desired and required in the transmitted and received picture with four channels in the communication system, the drum 1 would have four-eightieths of an inch of circumferential movement, with respect to each longitudinal movement of the scanning or reproducing system, imparted thereto, and for a similar increase 60 or decrease in the number of channels, the

line advance of the picture drum would be correspondingly changed.

To describe now the operation of the system when applied to a picture which is built up as a woven picture, such as has been described in connection with my copending applications, Serial Nos. 235,431 and 245,350, filed respectively November 25, 1927 and January 9, 1928, wherein I have disclosed what I have termed a forty-five degree transmitting and receiving picture machine, I will now move the gear 19 from the position as shown in the drawing so that it may be made to engage with the pinion 59 carried upon a shaft (not shown) extending through the housing member 35 and will then release a locking pin 61 so that the gear 59 may be free to turn when rotational movement is imparted thereto from a rotation of the pinion 19 carried upon the end of the shaft 7. It will thus be seen that as the gear or pinion 59 is rotated, the shaft 39 carrying the differential 41 will be constantly turned and thus the speed of the drum member 1 will be substantially increased over the speed imparted thereto by the rotation of the pinions 23, 29 and 31. By appropriately designing the gears, it will readily be seen when the beveled pinions 19 and 59 are placed into engagement that motion may be imparted to the drum 1 in such a manner that during the time the carriage for either analyzing or reproducing the picture is carried from one end of the shaft 7 to the other and back by reason of the support member 11 therefor sliding in the guides 13 and 15 that the drum may be made to turn a complete revolution plus an amount equal to a single line width of the picture, assuming the system to be applied to a single channel transmitting and receiving system.

Thus, at the time when the carriage supported by the support plate 11 moves in the opposite direction longitudinally of the shaft 7 upon reaching the end 63 of the spiral track that a line will be traced diagonally back across the picture surface carried by the drum 1, but spaced apart from the previous line of scanning or reproducing by an amount equal to the width of a single line of the picture. As the carriage carrying the scanning or reproducing system reaches the opposite end of the shaft 7 from that shown, the path of scanning or reproducing will be automatically changed, due to the relative movements, so that the analyzing light beam or the heat jet or light projected on a heat or light sensitive recording paper will trace a path across the record surface carried by the drum 1 in a direction diagonal of the first named path. As the motion of the carriage back and forth longitudinally of the shaft 7 is continued and rotary motion is imparted to the drum 1 by reason of the shaft 43 turning the worm

gear 49 and the gear 51, the scanning or reproducing action is continued and each successive line is spaced at the same predetermined distance from the preceding line, and scans or reproduces along parallel paths.

Now, where it is desired to increase the number of paths of scanning or reproducing of the picture in a manner similar to that above described in connection with the parallel line of scanning, the position of the gear shift lever in the slots 57 may be changed so that the drum 1 may be rotated a complete revolution plus an amount equal to the number of lines forming a multiplex system. Thus, supposing that four channels are utilized in the multiplex communication system, for each longitudinal movement of the carriage containing the scanning or analyzing system longitudinal with respect to the drum 1, the drum will be turned through one complete revolution plus an amount equal to four lines of scanning or reproducing.

For the purpose of framing the picture or adjusting the position of the drum 1 carrying the picture to be transmitted or the record surface on which the picture is to be received, I have provided a means whereby the drum may be rotated manually in one direction. I have provided for this system, a hand wheel 65 which is securely fastened to the shaft 53 supporting the drum 1 and supported from the gear 51 by any convenient and desired means, such as a pin 67, I have provided a pawl 69 which is adapted to engage with a ratchet wheel 71. The ratchet wheel 71 is also rigidly mounted with the shaft 53, and the pawl 69 rested thereon is spring pressed by means of a spring or other convenient form of arrangement 73. By turning the hand wheel 65 in a clockwise direction, as shown, the drum 1 may be rotated in this direction but the pawl engaging with the ratchet prevents turning the drum in the opposite direction.

While I have not herein shown or illustrated any means by which a picture to be transmitted or a record surface for recording a received picture may be fastened upon the drum 1, it is to be understood that I may provide any convenient and suitable type of supporting means, and, if desired, I may feed the paper or picture on to the drum 1 by a system similar to that disclosed and claimed in my copending application, Serial No. 360,065, filed May 3, 1929, and also I may provide a gripping means for securely gripping the picture or record surface, as shown, described, and claimed in the last named copending application.

In connection with line for line scanning, I may use a continuous feed paper system, where desired, but with a 45° scanning system it is preferable to cut a recording or picture sheet and feed this upon the record-

ing drum 1 in the manner outlined in my copending application, Serial No. 360,065, filed May 3, 1929, above referred to.

Also, in accordance with my present invention, I may provide a pair of adjacent transmitting and receiving drums, and parallel thereto arrange a similar driving spindle 7, provided with a pair of endless spiral driving tracks 9 (one being for guiding the motion of the analyzing or reproducing system associated with each drum). Thus, by using a duplex transmitting or receiving system, it will appear that I may transmit or receive two like or different pictures upon the same machine. In doing this, I transmit or receive each picture in a sequential manner, that is, the picture on one drum may be transmitted or received upon each stroke of the analyzing or reproducing carriage from left to right, for example, on shaft 7, and the other picture may be transmitted or received during each period of right to left travel of the second analyzing or reproducing system carried to be driven from shaft 7. Therefore, each separate picture is analyzed or reproduced only in one direction.

Further, by an appropriate arrangement of contact points, I may arrange a system whereby an alarm circuit is closed at each path of travel of the carriage or supporting plate 11 so that an indication of the end of transmission or reception may be had. Such a system has been claimed and described by my copending application Serial No. 360,063, filed May 3, 1929.

Various modifications from those herein suggested and illustrated in the present disclosure will at once suggest themselves and become apparent to those skilled in the art to which my invention is directed, and I, therefore, believe myself to be entitled to make any and all modifications which fall fairly within the spirit and scope of the invention as set forth in the hereinafter appended claims.

Having now described my invention, what I claim and desire to secure by Letters Patent is the following:

1. In a picture transmitting and receiving system, a support surface for the transmitted or received pictures, means for advancing a scanning system longitudinally with respect to said support means, and means for changing the path traced by said scanning system from parallel scanning to cross-screen scanning and vice versa.

2. A picture analyzing and reproducing system including a support surface for carrying a picture record, means for moving a scanning system longitudinally with respect to said support surface, means for rotating said record carrying surface at a rate commensurate with the type of scanning, and means for varying the speed of

rotation of said support surface and changing the speed in proportion to the time required for the scanning system to longitudinally traverse the said support surface.

3. A picture recording system including a support surface for a picture, means for rotating said support surface, a scanning system adjacent said support surface, means for moving said scanning system longitudinally with respect to said support surface, means for controlling the rate of rotation of said support surface in accordance with the time of travel of said scanning system longitudinally thereof, and means for changing the path traced by said scanning system over said support surface between parallel scanning and cross scanning.

4. In a picture reproducing system, a picture carrying drum, a scanning system adjacent to said drum, means for moving said scanning system back and forth longitudinally with respect to said drum, means for rotating said drum a predetermined amount for each longitudinal travel of said scanning system with respect thereto, and means for changing the speed of rotation of said drum from an amount equal to the line width of a single line of the picture to a complete turn of the drum plus an amount equal to the line width of a single picture for each complete longitudinal motion of the said scanning system back and forth with respect to said drum.

5. In a picture reproducing system, a record carrying drum, a scanning system, means for moving the said scanning system back and forth longitudinally with respect to said drum, means for advancing said drum carrying said record surface a predetermined amount for each longitudinal travel of said scanning system with respect thereto, and means for varying the amount of rotation of said drum in accordance with the number of paths of scanning thereon.

6. In a multiplex facsimile reproducing system, a record carrying drum, means for moving a scanning system longitudinally with respect thereto, means for varying the amount of rotation of said drum with respect to each longitudinal motion of said scanning means with respect thereto in accordance with the number of channels included in the multiplex system, and means for changing the path of travel traced by said scanning system with respect to said drum between parallel scanning and cross scanning in accordance with the amount of rotation imparted to said drum for each longitudinal movement of the said scanning system.

7. In a picture reproducing system, a record carrying drum, a scanning system associated therewith, means for moving the scanning system longitudinally in a reciprocating manner with respect to said drum,

means for advancing the said drum in a rotational manner an amount equal to the line advance of a single line of picture width for each longitudinal movement of the said scanning system with respect to said drum, means for changing the amount of rotation of said drum to a complete revolution plus the width of a single path of scanning on said drum for each longitudinal movement of the scanning system with respect to said drum for diagonal scanning.

8. A picture reproducing system as claimed in claim 7, including, in addition, means for increasing the amount of rotation of said drum for each longitudinal travel of the said scanning system with respect thereto by an amount equal to the number of channels in a multiplex communication system.

9. In a picture transmitting and receiving system having a support surface for the transmitted or receiving picture, and a scanning system for analyzing the picture, means for producing a relative motion between the scanning system and the picture supporting means, and means for changing the path traced by said scanning system relative to the picture supporting means from parallel scanning to cross-screen scanning and vice versa.

10. In a picture reproducing system having a record carrying drum and associated scanning system, means for producing a relative motion between said record carrying drum and said scanning system so that the scanning system moves longitudinally with respect to the record carrying drum during the rotation of the drum, and means for controlling the relative motion between said drum and said scanning system for changing the path traced by said scanning system from parallel scanning to cross-screen scanning and vice versa.
